(57) **CLAIM**

The ornamental design for a glucose meter, as shown and described.

DESCRIPTION

FIG. 1 is one perspective view of a glucose meter, showing my new design;

FIG. 2 is another perspective view thereof, opposite that shown in FIG. 1;

FIG. 3 is a side view thereof;

FIG. 4 is a side view thereof, opposite that shown in FIG. 3;

FIG. 5 is a top plan view thereof;

FIG. 6 is a bottom plan view thereof;

FIG. 7 is a front view thereof; and,

FIG. 8 is a rear view thereof.

The broken lines illustrate portions of the glucose meter that form no part of the claimed design.
